JOSEPH VINCENT, OF FRESNO, CALIFORNIA.

WASHING-MACHINE.

1,397,886.

Specification of Letters Patent. Patented Nov. 22, 1921.

Application filed April 30, 1919. Serial No. 293,807.

To all whom it may concern:

Be it known that I, JOSEPH VINCENT, a citizen of the United States, and resident of Fresno, in the county of Fresno and the 5 State of California, have invented a new and useful Improvement in Washing-Machines, of which the following is a specification.

My invention relates to a washing machine, having for its object the easy and thorough washing of clothes by means which will not tear or mutilate the fabric being washed. I accomplish these objects by means of the device hereinafter described 10 and illustrated on the accompanying drawings which are hereby made a part of this specification, in which Figure 1 is an end view of the washing machine complete. Fig. 2 is a cross-sectional view of the device. Fig. 20 3 is a perspective view of one of the swinging members used in the washer. Fig. 4 is an under view of the float.

In said drawing B is the outside form of the box or tub which is preferably rectangular in shape, having sides B¹ and B², the bottom B³, and the top or cover B⁴. The inside of the box is corrugated on its bottom, such corrugations being indicated on the drawing as 25. C and C¹ are a pair of 25 swinging members pivoted near the lower inside corners of the box B so that they can be swung toward the center line of the box B and so the water will be thoroughly agitated. To accomplish this readily I 30 have formed each of these swinging members with a back 4 having a plurality of perforations 5, and inside corrugations 25^a, an L extension 6 on the bottom with a pivot member 7 at each end thereof, and an ex- 35 tension 8 on the top. The extensions 6 and 8 are set at an obtuse angle to the back 4 as shown. At each end of the box B I have formed sockets 7^a into which pivotal exten- 40 sions 7 will fit. 9 is a weight attached to the back and near the top of swinging mem- 45 bers C and C¹. 10 is a strip the thickness of pivots 7 used for the purpose of preventing the clothes or fabric from being drawn under the hinge formed by socket 7^a and pivot 7. 6^a and 8^a are brace strips for strengthen- 50 ing extensions 6 and 8.

11 is a float which consists of a corrugated base 11^a and a weight on the top 11^b. This float has a plurality of holes 5^a there- 55 through. The weight 11^b should not be so heavy that float 11 will sink. 14 is an inside flange in box B near the top. D is a block on stand D^a which is supported by legs D¹. F are springs which rest on the block D and which carry box B on the top. It will be 60 noted that by filling the box with water or suds approximately to the flange 14, then placing float 11 on the top of the clothes with the corrugated side downward, by rocking the box the float 11 will move back 65 and forth over the top of the clothes thus giving them the same character of treat- 70 ment they would receive if rubbed lightly on a wash board, and the swinging member C and C¹ will also have a movement back 70 and forth with the water, and a portion of the water will go through the perforations. This movement of the water and gentle agi- 75 tation of the clothes over the corrugated surfaces is effectual in thoroughly cleans- 80 ing the clothes and imparting a rocking motion to the box through the spring F and is accomplished with a minimum effort. The box can be rocked by hand means, a handle G being shown for that purpose, or it can 85 be done by foot, a depending pedal E being shown for that purpose. E¹ is a weight on pedal E to give the rocking motion momentum. Other means for imparting this motion not shown may be used. 85

Inasmuch as better results are accom- 90 plished by using hot water, I have attached a small derrick to stand D for the purpose of lifting the float out of the tub. This derrick consists of an upright fulcrum 20, 90 at the top of which is pivoted a lever 21, having a balancing weight 22 at one end and a suspended hook 23^a at the other end. 23^b is an eye into which hook 23^a can be in- 95 serted to raise it out of the box. 23 is a rod connecting hook 23^a with lever 21.

I claim as new and ask for Letters Patent upon:

In a washing machine the combination of a rectangular box, two swinging members 100 within the box each of said swinging members being constructed with a rigid back and

two flanges along opposite edges of, and on the same side of the back and set at obtuse angles thereto one of said flanges on each swinging member being pivoted to the bottom of the box and on opposite sides, so that they can swing toward and from each other on their pivots, and weights attached to said

swinging members adjacent to the edges opposite the pivots, substantially as described.

JOSEPH VINCENT.
